ALLAN T. JOHNSTON, OF MOUNT LEBANON, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL RELAY

Application filed January 8, 1930. Serial No. 419,303.

My invention relates to electrical relays, and particularly to electrical relays adapted to be operated by alternating current. More particularly, my invention relates to alternating current relays of the type comprising a winding, and a contact which is operated at the expiration of a predetermined time interval of comparatively long duration after said winding becomes energized.

10. I will describe one form of electrical relay embodying my invention, and will then point out the novel features thereof in claims.

In the accompanying drawings, Fig. 1 is a top plan view of a relay embodying my invention with certain of the parts omitted to more clearly illustrate the construction. Fig. 2 is a front view of a portion of the relay illustrated in Fig. 1. Fig. 3 is a side view of a portion of the relay illustrated in Fig. 1, as it 20 appears when viewed from the right in Fig. 1.

Referring to the drawings, the reference character A designates a base plate which supports the operating parts of the relay. Mounted on two spaced vertical posts 1 25 formed integral with the base plate A, is an electromagnet B comprising two L-shaped laminated cores 2 as best seen in Fig. 3. The cores 2 are attached to the posts 1 by means of screws 3, and are arranged with their short legs 2^b confronting but spaced from each other by an air gap 4. Each short leg 2^b is provided with an energizing coil 5, which coils, as shown in Fig. 1, are connected in series, and are arranged to be supplied at times with alternating current from a suitable source such as the secondary 7 of a transformer T, over a switch 6. With the electromagnet B constructed in this manner, it will be apparent that the short legs 2^b constitute 45 one set of poles and the long legs 2^a constitute another set of poles. A ferrule 8 of copper or other electro-conductive material partially encloses the exposed end of each short leg 2^b to produce a shifting magnetic field when the coils 5 are supplied with alternating current.

The electromagnet B controls a laminated tractive armature 9, and a disk or vane 14 of electro-conductive, non-magnetic material such as aluminum. The armature 9 is pivoted 50 at one end on a stud 10 carried by a projection

11 of one of the posts 1, and is arranged to swing toward or away from the legs 2^a of the cores 2 of electromagnet B according as the coils 5 of electromagnet B are energized or de-energized. The motion of the armature 55 9 away from the legs 2^a of the cores 2 is limited by an adjustable back stop 55 screwed into the base plate A. Two ferrules 12 of electro-conductive material such as copper are fastened to the armature 9 to prevent 60 chattering of the armature when the armature is swung toward the legs 2^a of the cores 2 due to energization of the coils 5.

The vane 14 extends into the air gap 4 between the short legs 2^b of the cores 2, and is secured to a shaft 15 which is journaled at its ends in two trunnion screws 16 carried by two arms 17 projecting from the posts 1 (see Fig. 1). It will be apparent, therefore, that when the coils 5 of electromagnet B are energized, an electromagnetic torque will be exerted on the vane 14 by the shifting magnetic field which is set up in the cores 2, and the vane 14 will rotate.

The vane 14 is operatively connected, 75 through gearing C, with a movable arm G. The arm G, in the form here shown, comprises two parallel strips 19, rigidly fastened together at one end by means of a spacing stud 20, and pivotally supported at the other 80 end on a countershaft 21. The arm G also comprises a pinion 22 journaled in the strips 19, and meshing with an idler gear 23 mounted on a stud 24 attached to one of the strips 19. The idler gear 23, in turn, meshes with 85 a pinion 25 loosely journaled on the countershaft 21.

The countershaft 21 is mounted in two spaced plates 26 and 27 which are fastened by means of screws 31 to the opposite sides 90 of two standards 28 forming a part of a casting 29. The casting 29, in turn, is fastened to the base plate A by means of screws 30, and is provided with an upright member 32 which cooperates with the plate 26 to support part of the gearing C, which gearing I will now describe.

The gearing C, in the form here shown, comprises a pinion 18, secured to the vane shaft 15, and meshing with a gear wheel 33, 100

as best seen in Fig. 1. The gear wheel 33 is fastened to a shaft 34 which is journalled at one end in the upright member 32 of the casting 29 and, at the other end, in the plate 26. The shaft 34 also carries a pinion 35, which is fixed to this shaft, and which meshes with a gear wheel 36. The gear wheel 36 is secured to a shaft 37 journalled in the plates 26 and 27 and has attached thereto, or formed 10 integral therewith, a pinion 38, which drives a gear wheel 39. The gear wheel 39, in turn, is fastened to the countershaft 21, and meshes with the pinion 22 of the movable arm G hereinbefore described.

15 Cooperating with the pinion 25 is a dog 40 which is pivoted at one end on a pin 43 carried by two spaced lugs 44 formed on one of the standards 28 (see Figs. 1 and 2). The other end of the dog 40 is bent upwardly and 20 is tapered for engagement with the teeth of the pinion 25. The dog 40 is adapted to be operated by the armature 9 and, for the purpose of connecting the dog with the armature, the dog is provided with a hole 40^b 25 (Fig. 2) which receives a stud 42 with considerable clearance at a portion 42^a having a smaller diameter than the body of the stud. The stud 42 is fastened to one end of a bracket 41, the other end of which is fastened 30 to the free end of armature 9, as best seen in Fig. 3. With the parts arranged in this manner, it will be seen that when the coils 5 of electromagnet B are energized so that armature 9 is drawn upwardly against the legs 35 2^a of the cores 2, the dog 40 will be swung upwardly about the pin 43 to a position in which its tapered end engages the pinion 25, thereby preventing rotation of the pinion 25.

The arm G operates contact apparatus 40 here shown as comprising a rocker 45, pivotally mounted at 45^a, and provided with a horizontal arm 46 which is pivotally connected with the upper end of a link 47. The lower end of the link 47 is provided with a 45 slot 47^a which receives the spacing stud 20 of the movable arm G. The rocker 45 carries two contact fingers 49 and 50 which cooperate with two fixed contacts 49^a and 50^a, respectively, to close a contact 49—49^a or 50—50^a, as will be explained hereinafter. The rocker 45 also carries a bar 51 and a counterweight 54. The bar 51 cooperates with adjustable front and back stop screws 52 in a fixed block 53 to restrict the motion 55 of the rocker 45 to the desired limits. The counterweight 54 serves to bias the rocker to a position in which the contact 50—50^a is closed and the contact 49—49^a is open as shown in the drawings.

60 The operation of the relay is as follows: When switch 6 is open, the coils 5 of electromagnet B are deenergized, so that vane 14 is at rest, and armature 9 is swung away from the legs 2^a of the cores 2. The dog 40 is 65 then out of engagement with the pinion 25

and the pinion 25 is therefore free to rotate on the countershaft 21. Under these conditions, the movable arm G engages an adjustable backstop 48^a screwed in a boss 48 of the casting 29. When the arm G occupies this 70 position, the pin 20 of this arm occupies an intermediate position in the slot 47^a of the link 47, and the counterweight 54 therefore holds the rocker 45 in the position in which contact 50—50^a is closed and contact 49—49^a is open.

I will now assume that switch 6 becomes closed. Alternating current is then supplied to the coils 5 of electromagnet B from the secondary 7 of transformer T, and an alternating flux is set up in the cores 2 of electromagnet B. Armature 9 therefore picks up and moves dog 40 into engagement with the pinion 25, so that rotation of the pinion 25 about the countershaft 21 is prevented and, at the same time, vane 14 starts to rotate. The rotation of the vane 14 is transmitted through the gearing C to the pinion 22 of the arm G which, in turn, drives idler gear 23, and the parts are so arranged that this gear turns 85 in a counter-clockwise direction as viewed in Fig. 2. Since pinion 25 is now prevented from rotating by dog 40, it will be apparent that the rotation of the idler gear 23 causes the arm G to rotate about the countershaft 21 in the same direction as the idler gear is rotating. As the arm G rotates in this direction, the stud 20 slides upwardly in the slot 47^a of link 47 until it engages the upper 90 end of this slot, whereupon it operates rocker 45 to open contact 50—50^a and close contact 49—49^a. The vane 14 will continue to rotate until bar 51 engages the lower stop screw 52, at which time further motion of the bar and hence further rotation of the vane is prevented. The rocker 45 is then held in the 95 position in which the bar 51 engages the lower stop screw 52 until switch 6 is opened to de-energize the coils 5 of electromagnet B. When this is done, the armature 9 drops, thereby moving dog 40 out of engagement with the pinion 25. Since the pinion 25 is then free to rotate about the countershaft 21, arm G immediately returns by gravity to its lower position in which it engages the backstop 48^a. Stud 20 is then withdrawn from engagement with the upper end of slot 47^a in the link 47, and counterweight 54 therefore operates rocker 45 to open contact 49—49^a and close contact 50—50^a. All parts 100 are then restored to the positions in which they are illustrated in the drawings.

110 It will be apparent from the foregoing that a considerable interval of time elapses after the coils 5 of electromagnet B become energized before contact 50—50^a is opened and contact 49—49^a becomes closed. It will also 115 be apparent from an inspection of the drawings that the length of this time interval depends upon the angular distance through 120 125 130

which the arm G must be rotated before the stud 20 of the arm G engages the upper end of the slot 47^a in the link 47, the speed of the vane 14, and the gear ratios of the gears comprising the gearing C. The angle through which the arm G has to move before the pin 20 engages the upper end of the slot 47^a in the link 47 may be increased or decreased by lowering or raising the backstop 48^a, and the gear ratios of the gears comprising the gearing C may be varied by replacing the gears with other gears having the desired ratio. It follows, therefore, that the time interval which elapses after the coils 5 of the electromagnet B are energized before contact 50—50^a is opened and contact 49—49^a becomes closed, may be adjusted to any desired value.

It will also be apparent from the foregoing that when the coils 5 of electromagnet B become de-energized after contact 50—50^a has been opened and contact 49—49^a has been closed, contact 49—49^a becomes opened immediately and contact 50—50^a becomes closed immediately. It follows that I have provided an alternating current relay having one contact which does not close until the expiration of a measured time interval of comparatively long duration after the relay becomes energized but which opens immediately upon the de-energization of the relay, and another contact which does not open until the expiration of said time interval after the relay becomes energized but which closes immediately upon the de-energization of the relay.

Although I have herein shown and described only one form of electrical relay embodying my invention, it is understood that various changes and modifications may be made therein within the scope of the appended claims without departing from the spirit and scope of my invention.

Having thus described my invention, what I claim is:

1. In combination, an electromagnet having two sets of poles, means for at times energizing said electromagnet, a vane adapted to rotate between one set of poles when said electromagnet is energized, a tractive armature which is moved toward the other set of poles when said electromagnet is energized, a normally closed contact, means controlled by said vane and said armature for opening said contact upon the operation of a predetermined time interval after said electromagnet becomes energized, and means independent of said first mentioned means for restoring said contact if said armature moves away from said other set of poles.

2. In combination, an alternating current electromagnet, means for at times energizing said electromagnet, a vane arranged to be rotated by said electromagnet when said electromagnet is energized, a tractive armature movable toward and away from said electro-

magnet according as said electromagnet is energized or de-energized, a contact, means controlled by said vane and said armature for operating said contact upon the expiration of a predetermined time interval after said electromagnet becomes energized, and means for varying the length of said time interval.

3. In combination, an electromagnet, means for at times energizing said electromagnet, a first member which is rotated when said electromagnet is energized, a second rotatable member, means controlled by said electromagnet for preventing rotation of said second rotatable member when said electromagnet is energized, a third member, means controlled by said first member for rotating said third member about said first member when and only when said second member is prevented from rotating, and a contact controlled by said third member.

4. In combination, an electromagnet, means for at times energizing said electromagnet, a first member adapted to be rotated by said electromagnet when said electromagnet is energized, a second member movable toward and away from said electromagnet according as said electromagnet is energized or de-energized, a third rotatable member, means controlled by said first member for rotating said third member when and only when said second member is moved toward said electromagnet, and a contact operated by said third member.

5. In combination, an electromagnet, means for at times energizing said electromagnet, a first member adapted to be rotated by said electromagnet when said electromagnet is energized, a second member movable toward and away from said electromagnet according as said electromagnet is energized or de-energized, a third member biased to a first position but movable to a second position, means controlled by said first member for moving said third member from its first position to its second position if said second member is moved toward said electromagnet, and a contact controlled by said third member.

6. In combination, a countershaft, a first pinion journalled on said countershaft, an arm pivotally supported on said countershaft and biased by gravity to a predetermined position, said arm being provided with a second rotatable pinion and with an idler gear for connecting said second pinion with said first pinion, an electromagnet, means controlled by said electromagnet and effective when said electromagnet is energized for at times rotating said second pinion, means also controlled by said electromagnet and effective when said electromagnet is energized for preventing rotating of said first pinion whereby said arm is made to rotate about said countershaft in response to rotation of said second pinion, and a contact controlled by said arm.

7. In combination, an electromagnet, means for at times energizing said electromagnet, a vane adapted to be rotated by said electromagnet when said electromagnet is energized, a tractive armature movable toward and away from said electromagnet according as said electromagnet is energized or de-energized, a countershaft, a first pinion loosely journaled on said countershaft, a movable 10 arm comprising two spaced strips rigidly secured together at one end by a spacing stud and pivotally supported at the other end on said shaft, said arm also comprising a second pinion journaled in said strips and an idler 15 gear journaled on a stud carried by one of said strips, said idler gear being arranged to mesh with both said first and second pinions, gearing connected between said vane and said second pinion for at times rotating said second pinion in response to rotation of said vane, a pivoted dog, means attached to said armature for moving said dog into engagement with said first pinion when said armature is moved toward said electromagnet to 20 prevent said first pinion from rotating, and a contact controlled by said movable arm.

8. A relay comprising an electromagnet, a vane adapted to be rotated when said electromagnet is energized, a tractive armature 30 which is moved toward or away from said electromagnet according as said electromagnet is energized or deenergized, a dog which is moved from a first position to a second position when said tractive armature is moved 35 toward said electromagnet, a contact, and means independent of said armature for operating said contact in response to rotation of said vane if and only if said dog occupies its second position.

40 9. A relay comprising an electromagnet, a vane adapted to be rotated when said electromagnet is energized, a tractive armature which is moved toward or away from said electromagnet according as said electromagnet is energized or deenergized, a member 45 which is moved to a first or a second position according as said tractive armature is moved toward or away from said electromagnet, a contact, means responsive to rotation of said vane if and only if said member occupies its first position for operating said contact, and other means effective when said contact has 50 been operated for restoring said contact when said member is subsequently moved to its second position.

55 10. A relay comprising an electromagnet, a vane which is rotated by said electromagnet when said electromagnet becomes energized, a counter-shaft, gearing for connecting said 60 vane and said counter-shaft in such manner that said counter-shaft is rotated in response to rotation of said vane, a pinion loosely journaled on said counter-shaft, a tractive armature arranged to be moved toward or away 65 from said electromagnet according as said

electromagnet is energized or deenergized, a dog controlled by said armature and arranged to be moved into engagement with said pinion to prevent rotation of said pinion when and only when said armature is moved toward said electromagnet, an arm journaled on said counter-shaft and biased to one position, means associated with said arm and responsive to rotation of said counter-shaft for rotating said arm away from said one position when and only when said pinion is prevented from rotating, and a contact controlled by said arm.

In testimony whereof I affix my signature
ALLAN T. JOHNSTON.
